UNITED STATES PATENT OFFICE.

WILLIAM L. CARTER, OF WATERLOO, IOWA, ASSIGNOR TO WATERLOO REGISTER COMPANY, OF WATERLOO, IOWA.

NURSERY-CHAIR.

1,039,647.

Specification of Letters Patent. Patented Sept. 24, 1912.

Application filed May 17, 1911, Serial No. 627,767. Renewed June 8, 1912. Serial No. 702,618.

To all whom it may concern:

Be it known that I, WILLIAM L. CARTER, a citizen of the United States of America, and a resident of Waterloo, Blackhawk county, Iowa, have invented certain new and useful Improvements in Nursery-Chairs, of which the following is a specification.

My invention relates to improvements in nursery chairs, and the object of my improvement is to provide a combined seat and tray attachment adapted to be removably supported on the back of an ordinary chair, said device having its said parts adjustable, and also foldable when not in use. This object I have accomplished by the means which are hereinafter described and claimed, and which are illustrated in the accompanying drawings, in which:

Figure 1 is a side elevation of an ordinary chair, showing my improved foldable and adjustable nursery chair attachment supported removably thereon, with the tray and seat adjusted and extended outwardly as in use. Fig. 2 is a perspective view of said attachment, showing the seat and tray extended outwardly. Fig. 3 is a side elevation of said attachment, showing it with its seat and tray folded up against their supporting means. Fig. 4 is a front elevation of the supporting rods of said device, showing the tray removed, and the seat extended outwardly. Fig. 5 is an enlarged detail view of one of the seat brackets. Fig. 6 is an enlarged detail side elevation of one of the sliding connections between the tray-arms and supporting rod, showing the fastening clip in position securing said tray arm in an outwardly extended position.

Similar numerals of reference designate corresponding parts throughout the several views.

The numeral 23 designates an ordinary chair, on whose top cross-bar 24 my chair attachment is removably suspended. The chair-attachment body or supporting frame consists of a rod 1 which is bent so as to present two spaced apart parallel depending members connected by a part 2, the latter being recurved rearwardly and downwardly to form a shallow loop covered at the middle only with a rubber tube or sleeve 3, as also at the angles at 4 by similar sleeves to prevent injury to the chair 23. The lower ends of the depending members 1 are in like

manner covered by removable sleeves 5 of soft rubber for a like purpose.

The seat 18 is supplied on each side at the rear with metal brackets 15 secured by means of the screws 22. These brackets have laterally extending projections 14, 16 and 17. The depending rods 1 have oppositely-located orifices 13, in a desired plurality to permit of the up or down adjustment of said seat along the rods. The projections 17 of said brackets are to be detachably seated in oppositely located orifices 13 of said rods, which is effected by springing the lower ends of the rods 1 apart. The projections 14 and 16 on said brackets are adapted to respectively engage the rear and forward sides of the rods 1 to limit the swinging movement of the seat 18, the projections 14 and 16 co-operating to hold the seat steadily horizontal when in its dropped outwardly-extended position for use. Above said seat is located a swinging tray 20 having metal arms 19 secured thereto by means of screws or bolts 21. The rear ends of the arms 19 are bent downwardly and located adjacently to the rod members 1. The numeral 6 designates sleeve-like bodies which are seated slidably upon the rod-members 1 oppositely, and whose forwardly extending parallel lugs 12 have oppositely located orifices to pivotally receive the ends of pins 7 projecting oppositely from the angles of said arms 19. The downwardly-turned ends of said arms, when the arms are horizontal, engage the forward parts of the rods 1 and limit the downward movement of said tray 20. The numerals 8 and 10 designate studs which respectively project laterally on the same side, of each of the sleeve-like bodies 6 and the down-turned ends of the arms 19. Upon the stud 8 on each body is pivotally mounted a clip 9 whose end is projected to form a finger-piece, and which has a projection 11. This projection 11 is so formed and directed relatively to the body of the clip, that a somewhat narrow recess is provided therebetween, and when the arm 19 is horizontally extended, as shown in Fig. 1, the clip may be swung on its pivot so as to cause the projection 11 to engage the stud 10 and seat itself thereover with the stud detachably secured in the narrow end of said recess. By this means the downwardly-turned end of

the arm 19 is firmly bound and locked against the adjacent contacting rod-member 1, which renders the tray 20 firm on its supports. When the clip is disengaged from 5 said stud 10 by swinging it up and backwardly, the arms 19 may be swung upwardly against the rods 1. If the seat 18 has been first swung upwardly to its limit, as shown in Fig. 3, and the slidable bodies 10 6 permitted to slip downwardly along the rods 1, the clips 9 having been first disengaged, the tray 20 may be swung upwardly, in which position the lower inner edge of 15 the tray engages the upturned outer edge of the seat 18, securing the latter. In this folded condition, the device is very compact and may be easily transported from place to place or stowed away occupying but little space until wanted for use. In use the device 20 is suspended with the connecting part 2 of the rods 1 hung over the upper cross-bar of the supporting chair as shown.

When a child has been seated upon the seat 18, the bodies 6 may be slid downwardly along the rods 1, and then the clips 9 secured on the studs 10, leaving the tray 20 in a position where it lies closely to or upon the child's lap, and secures the child on the seat so that it cannot fall off the seat. The 30 seat 18 may be adjusted up or down on said rods 1 by merely locating the bracket-studs 17 in other orifices 13 of said rods.

It is to be understood that slight variations in the form of this device will come 35 within the scope of the protection of my said invention.

Having described my invention, what I claim as new, and desire to secure by Letters Patent, is:

40 1. In a nursery chair, spaced apart connected rods, bearing-bodies slidable on said rods, a tray having spaced apart arms turned down at an angle at their ends and pivoted at their angles to said bodies, laterally directed studs on the turned-down parts of 45 said arms, and clips pivoted to said bodies and adapted to detachably engage said studs

to hold said tray in an outwardly-extended position.

2. In a nursery chair, spaced apart connected rods, bearing-bodies slidable on said rods, a tray having spaced apart arms turned down at an angle at their ends and pivotally connected at their angles to said bodies, laterally-directed studs on the turned-down parts of said arms, clips pivoted to said bodies and adapted to detachably engage said studs to hold said tray locked in an outwardly-extended position, said rods having a plurality of oppositely-located orifices, 60 a seat, brackets secured on said seat having studs removably and pivotally seated in certain of said orifices, and means for limiting the amount of movement of said seat to and from said rods. 65

3. In a nursery chair, spaced apart connected rod-members, bearing-bodies slidably mounted on said members opposite each other and having spaced apart lugs, a tray having spaced apart arms turned down at 70 an angle at their ends and pivoted at their angles to the lugs on said slidable bodies, clips pivotally connected to said slidable bodies, laterally-directed studs on the downturned ends of said arms, said clips being 75 adapted to detachably engage said studs to lock the downturned ends of the arms to hold said tray in an outwardly-extended position, said rods having a plurality of oppositely-arranged orifices, a seat, brackets on 80 said seat having laterally-directed studs adapted to be detachably and pivotally mounted in certain of said orifices adjustably along said rods, and means for limiting the movement of said seat up or down 85 relatively to said rods, the connecting part between said rod-members being recurved to adapt it to be suspended from a support.

Signed at Waterloo, Iowa, this 29th day of April, 1911.

WILLIAM L. CARTER.
